BARBER CHAIR OR SIMILAR ARTICLE

John A. Dlouhy, Oak Park, Ill., assignor to Emil J. Paidar Company, Chicago, Ill., a corporation of Illinois

Filed Sept. 11, 1961, Ser. No. 66,695

Term of patent 14 years

(Cl. D15—3)

FIG. 1

FIG. 2

FIGURE 1 is a front perspective view of a barber chair or similar article showing my new design; and

FIGURE 2 is a perspective view taken from the side of the chair.

The surfaces not shown, including the back of the chair, are substantially plain.

The design is characterized by the trapezoidally-shaped armrest support panel, in combination with the remainder of the chair, all as shown.

I claim:

The ornamental design for a barber chair or similar article, as shown and described.
